VALVE ACTUATOR AND DISPENSING HEAD FOR A PRESSURIZED CONTAINER

Paul M. Kotuby, Naugatuck, Conn., assignor to The Risdon Manufacturing Company, Naugatuck, Conn.

Filed Mar. 5, 1973, Ser. No. 338,159

Term of patent 14 years

Int. Cl. D9—07

U.S. Cl. D9—258

FIG. 1.

FIG. 2.

FIG. 3.

FIG. 4.

FIG. 1 is a perspective view of a valve actuator and dispensing head for a pressurized container showing my new design;

FIG. 2 is a side elevational view;

FIG. 3 is a top plan view; and

FIG. 4 is a bottom plan view.

I claim:

The ornamental design for a valve actuator and dispensing head for a pressurized container, substantially as shown and described.
